UNITED STATES PATENT OFFICE.

DAVID NEALE, OF FORT CALHOUN, NEBRASKA.

MUD-CHAMBER.

SPECIFICATION forming part of Letters Patent No. 716,572, dated December 23, 1902.

Application filed January 23, 1901. Serial No. 44,487. (No model.)

To all whom it may concern:

Be it known that I, DAVID NEALE, residing at Fort Calhoun, in the county of Washington and State of Nebraska, have invented certain 5 useful Improvements in Mud-Chambers; and I do hereby declare that the following is a full, clear, and exact description of the invention, such as will enable others skilled in the art to which it appertains to make and use the 10 same, reference being had to the accompanying drawings, which form a part of this specification.

This invention relates to an improvement in permeable cells forming mud-chambers, 15 adapted to be used in building moles, dikes, or dams to be placed in streams to reduce the width of the same and to direct and control its flow to prevent the scour of its bed and guard against caving in of its banks.

20 In carrying out the object of my invention I provide a light portable cell of permeable material and of any suitable shape, which cell has one open end, the remaining sides of the cell being entirely closed.

25 In the accompanying drawings I have shown in Figure 1 a perspective view of one of my cells. Fig. 2 shows a simple method of uniting the side sills and transverse bars, while Fig. 3 shows an end view of a cell 30 which is hollow, but triangular in cross-section.

As has been set forth, the aim of my invention is to provide a structure of permeable material open at one end, which may be sunk 35 or otherwise lowered into a river and which gradually becomes filled with silt and other heavy drift material within the river, and so forms a solid compact mass in course of time sufficient to offer a lasting obstruction to the

40 water-current.

In following out the aim of my invention I use two counterpart side sills A A and two similar sills B, in the drawings but one of these sills being shown. The sills A A are 45 connected by means of a number of transverse slats or boards *a*, and the counterpart sills B are united by means of a series of transverse slats *c*, as is shown more clearly in Fig. 1. These sills A and B and the slats 50 *a* and *c* form two sides, which are united by

means of the rods 2 2, these rods 2 connecting the transverse slats *a* and *c* and the rods 1 1, which extend through the sills and slats and form a holder or support, as it were, for the permeable material *x*, which may comprise brush, cornstalks, or the like, and in it is secured by any suitable means about the hollow frame structure forming the support or shell of the frame. Above, the permeable material is made to pass above and below the 60 permeable material between the sills A and B and the permeable material between the rods 1 and 2. In Fig. 2 I have shown a simple method of connecting the sills by means of these rods 1 and 2, which are slotted at the 65 ends and are provided with suitable wedges *z*, which secure the framework sufficient to form a permeable structure, which is sunk by any suitable means into the river to gradually fill up and form a solid chamber. 70

If desired, the cells may be made three-cornered in providing a number of frame-pieces 3 to form a triangle, which are united at the ends by means of suitable strap-iron, as is shown at 4, upon which frame-pieces 3 75 the brush or other material is packed, the material being secured to these triangular frame-pieces 3 by means of the outer slats 5, these slats being united by means of suitable sills 6, which extend from one frame-section to the other. Upon the outside these frame pieces or sections 5 are secured by means of the strap-iron bindings 7. This structure is exactly like the one just described, with the exception that it is triangular instead of being square. These cells in 80 order to be strengthened later may be provided with encircling wire-sections *y* to increase the strength.

It will be noticed that the cells herewith 90 shown are open at one end or have one side removed, while all the remaining sides are closed. In closing the ends the brush is projected beyond the same and closed by means of the wire strand *x'*, as is shown in Fig. 1. 95 These cells may be made of any suitable size or length and form permeable units or elements, which may be united to form mats or fascines, which are secured in silt-bearing streams to become filled and solid within the 100

course of time, so as to form a permanent and solid obstruction within the current.

Having thus described my said invention, what I claim as new, and desire to secure by

5 Letters Patent, is—

A cell comprising a suitable structure of permeable material said cell being open at

one end and having the opposite remaining end closed as and for the purpose set forth.

DAVID NEALE.

In presence of—

GEORGE W. SUES,
R. J. DAVENPORT.
